10 Claims. (Cl. 178—44)

This invention relates to coupling devices for electrical circuits and is particularly adapted for use in superheterodyne radio receivers. The general object of the invention is to provide a novel 5 transformer or coupling device in which the frequency response or band width may be varied. As is well known, in superheterodyne radio receivers the extent of the audio frequency range of the receiver is determined by the band width of the 10 intermediate frequency system as well as by other frequency selective systems which may be incorporated in the receiver. In order to obtain "high fidelity" response it is necessary to provide means by which the side bands of the modulated carrier 15 wave signal may be transmitted without being markedly attenuated. The invention provides means for broadening the response so as to obtain "high fidelity", at the same time maintaining the gain of the receiver substantially uniform.

20 A further object of the invention is to provide a circuit by which the fidelity curve or response curve of the receiver may be varied manually without the use of expensive or complicated parts.

The invention may be fully understood from the 25 following detailed description in connection with the illustrative embodiments of the accompanying drawings. In the drawings:

Figure 1 is a schematic illustration of a simple 30 circuit employing the novel features of the invention;

Fig. 2 illustrates typical response curves which 35 may be obtained by means of the novel features provided by the invention;

Fig. 3 illustrates the intermediate frequency portion of a radio receiver employing the features 40 of the invention; and

Fig. 4 illustrates a typical response curve of the 45 radio frequency portion of a radio receiver and the resultant curve obtained by the use of this invention.

Referring particularly to Fig. 1 of the drawings, there are shown two conventional vacuum tubes 50 V₁ and V₂ coupled by means of a tuned transformer T embodying the features of the invention, as will be fully described hereinafter. The tube V₁ may be energized by a suitable source of electrical waves or oscillations E. This source may take the form of any suitable signal source.

The transformer T comprises a primary winding 55 L₁ and a secondary winding inductively coupled thereto comprising portions L₂ and L₃, the purpose of which will be clearly understood from the subsequent description. The primary winding L₁ is included in the output circuit of the tube V₁, while the secondary winding L₂, L₃ is included

in the input circuit of tube V₂ in conventional manner. A condenser or capacitance C₁ is associated with the primary winding L₁, one side of the condenser being connected directly to an extremity of the primary winding as at 1, while the other side of the condenser is connected to the movable contact 2 of a switch S. The switch S also comprises stationary contacts 3 and 4 arranged for selective engagement by the movable contact 2. The stationary contact 3 is connected to a point 5 of the secondary winding, which point divides the said winding into the portions L₂ and L₃. A condenser C₂ is connected across the secondary winding in conventional manner.

The extremity of the primary winding L₁ opposite the point 1 may be connected to ground through a blocking condenser C₃ and the corresponding extremity of the secondary winding may be likewise connected to ground through a blocking condenser C₄. While this arrangement is preferred, it will be understood that an alternative arrangement may be employed in which the extremities in question of the transformer windings are connected together through a single blocking condenser.

It will be seen that when the movable contact 2 of switch S is in engagement with the stationary contact 4, the circuit comprises a conventional tuned transformer circuit and, if the inductive coupling between the transformer windings is critical or slightly less than critical, the frequency response or transmission characteristic of the system will be substantially as illustrated by the frequency response curve 6 of Fig. 2. When the movable contact 2 of switch S is in engagement with the stationary contact 3, however, the portion L₃ of the secondary winding is included in circuit with the condenser C₁ and the inductive coupling between the two windings is increased by an amount corresponding to the inductance of portion L₃ which is common to both windings. In other words, the degree of coupling between the tuned primary and secondary circuits is increased and the said circuits are, at the same time, detuned to a limited extent. The frequency response or transmission characteristic of the system is now substantially as shown by the frequency response curve 7 of Fig. 2. It will be understood that the dividing point of the secondary winding may be chosen to give the desired response characteristic.

It will be noted that the broader response curve 7 has two peaks spaced on opposite sides of the peak of the original curve 6, there being a slight depression between the two peaks. In order that

the peaks of the response curves 7 shall be similar and equally spaced on each side of the single peak of the curve 6, and in order that this condition shall be maintained and displacement prevented, or in other words in order that the symmetry of the two peaks shall be maintained, the following relation should exist:

$$M_{12} + M_{13} = S\sqrt{L_1 L_2}$$

10 where M_{12} = mutual inductance in henrys between the primary winding and the portion L_2 of the secondary winding

15 M_{13} = mutual inductance in henrys between the primary winding and the portion L_3 of the secondary winding

$$S = \frac{\text{turns in whole secondary}}{\text{turns in primary}}$$

20 L_1 and L_2 are the self inductance in henrys of the primary winding and the portion L_2 of the secondary winding, respectively.

25 With this condition existing, the peak spacing may be defined in terms of the circuit characteristics as follows:

$$\begin{aligned} \text{Peak spacing} &= \frac{1}{L_1 \sqrt{L_1 C_1}} \left(\frac{M_{13}}{S} + \sqrt{L_1 L_2} \right) \text{cycles} \\ 30 &= \frac{\omega}{L_1} \left(\frac{M_{13}}{S} + \sqrt{L_1 L_2} \right) \text{cycles} \end{aligned}$$

where $\omega = 2\pi f$

f = frequency in cycles to which the primary and secondary circuits are resonant each in the absence of the other

35 C_1 = capacity of condenser C_1 in farads.

These results have been derived under the assumption that the resistance of the circuits may be neglected except insofar as they are necessary in order to determine critical coupling, and further that for the position of minimum band width, the primary and secondary circuits will be tuned to the same frequency, and that the primary and secondary will be less than critically coupled.

40 For the case in which these relations are not satisfied there will be a slight band displacement to one side or the other. It has been found, however, that this displacement is relatively slight and will not be objectionable. Consequently, if 45 desired more than two taps may be placed in the secondary and several degrees of band width may be obtained. The curves shown in Fig. 2 represent the case wherein the secondary winding comprised 400 turns of wire tapped at the 10th and 50 20th turns up from the bottom. In this particular case, the response curves 6 and 8, corresponding to minimum and intermediate band width, were adjusted according to the above formula and were symmetrical within the degree of precision 55 of the measurements. The third curve 7, taken with the condenser C_1 connected to the 20th turn tap, was displaced from the symmetrical position by an amount corresponding to about 4 percent of the band width.

60 While the invention is directed particularly to superheterodyne radio receivers as above stated, the features of the invention illustrated in Figs. 1 and 2 of the drawings, are capable of general use. In other words, in its broad aspect, the invention 65 is directed to electrical transmission systems and is, therefore, to be so considered.

In Fig. 3, the invention is illustrated as applied to a conventional superheterodyne radio receiver.

In this specific illustration, there is shown a 70 portion of the first detector stage, an intermediate

frequency stage, and a portion of the second detector stage. It will be understood, of course, that the intermediate frequency portion of the receiver may comprise one or more vacuum tube stages, as is well understood, and the detector stages may be varied in accordance with known practice. It will be also understood that the usual antenna circuit may be provided and conventional radio and audio frequency amplifiers each comprising one or more stages may be employed, and a sound reproducing device may be connected to the output of the system, although these conventional elements are not shown.

Following the teachings of the invention, there are provided tuned transformers T_1 and T_2 which are generally similar to the transformer T of Fig. 15

1. Selective switches S_1 and S_2 are associated respectively with the transformers T_1 and T_2 . In order to provide three degrees of fidelity of the receiver, each of the switches S_1 and S_2 comprises stationary contacts 9, 10, and 11, the contacts 10 and 11 being connected respectively to points 12 and 13 on the associated secondary winding. The switches S_1 and S_2 may be adapted for simultaneous or tandem operation in conventional manner, as indicated by the broken-line representation.

When the switches are adjusted to the contact position 9, minimum band width is provided, as will be understood from the foregoing description. Adjustment of switches S_1 and S_2 to the contact positions 10 and 11 selectively increases the fidelity from the minimum to the maximum. It will be understood that the device provided by the invention may be employed to couple each of the stages of the intermediate frequency amplifier, as well as to couple the said amplifier to the detectors, or to couple the detectors to each other.

It should be borne in mind that the frequency response or transmission characteristic of each of the portions of the receiver other than the intermediate frequency portion should be sufficiently broad so as not to reduce the over-all frequency response of the receiver when adjusted for maximum fidelity. In other words, assuming a maximum frequency response such as illustrated by curve 7 of Fig. 2, the frequency response of each of the said other portions of the receiver should be broader than the response curve 7. In general, this condition is satisfactorily met in practice using conventional elements in the said other portions of the receiver but, if necessary or desired, the device of the present invention, as illustrated in Fig. 1, may be used in other portions of the receiver to obtain the requisite breadth of frequency response.

The conventional radio frequency amplifier comprising one or more stages usually has a frequency response or transmission characteristic such as illustrated by curve 14 of Fig. 4. This response curve is generally broader than the response curves shown in Fig. 2 and has a broad peak coincident with the central depressions in the curves 7 and 8 of Fig. 2. When the receiver is adjusted for increased fidelity to give a response such as illustrated by the curves 7 and 8 of Fig. 2, the over-all response of the receiver will be substantially as illustrated by the curve 15 of Fig. 4 which represents the resultant of the response of the radio frequency stages and the intermediate frequency stages. It will be seen that the central depressions of the response curves 7 and 8 are substantially balanced out by the peak of the curve 14 so that the over-all response curve 15 is substantially flat along its 75

crest. Thus the over-all gain of the receiver is maintained substantially uniform.

Automatic volume control may be incorporated in the receiver as illustrated in Fig. 3. The volume control voltage may be derived from a suitable source, such as the input circuit of the second detector, and may be applied to one or more of the preceding amplifier stages.

Although the invention has been illustrated and described with reference to certain specific embodiments for the purpose of disclosure, it will be understood that various changes and modifications may be made without departing from the spirit and scope of the invention, and that the invention is capable of broad adaptation as above stated.

I claim:

1. In a tuned coupling device, the combination of an inductive reactance, a capacitive reactance having one connection in common with said inductive reactance, said reactances comprising a tuned circuit, a second inductive reactance, a second capacitive reactance having one connection in common with said second inductive reactance, said last named reactances comprising a second tuned circuit, said first tuned circuit and said second tuned circuit being coupled one to the other, low impedance means connecting said first tuned circuit and said second tuned circuit, and switching means for effectively including a selected portion of a reactance of one of said tuned circuits in circuit with a reactance of the other of said tuned circuits, to thereby simultaneously vary the tuning of and coupling between said circuits.

2. In a tuned coupling device, the combination of an inductive reactance, a capacitive reactance having one connection in common with said inductive reactance, said reactances comprising a tuned circuit, a second inductive reactance, a second capacitive reactance having one connection in common with said second inductive reactance, said last named reactances comprising a second tuned circuit, said first tuned circuit being electromagnetically coupled to said second tuned circuit, low impedance means connecting said first tuned circuit and said second tuned circuit, and switching means for effectively including a selected portion of a reactance of one of said tuned circuits in circuit with a reactance of the other of said tuned circuits to thereby simultaneously vary the tuning of and coupling between said circuits.

3. In a tuned coupling device, the combination of an inductive reactance, a capacitive reactance having one connection in common with said inductive reactance, said reactances comprising a tuned circuit, a second inductive reactance, a second capacitive reactance having one connection in common with said second inductive reactance, said last named reactances comprising a second tuned circuit, said first tuned circuit and said second tuned circuit being resonant to substantially the same frequency and being coupled one to the other, low impedance means connecting said first tuned circuit and said second tuned circuit, and switching means for effectively including a selected portion of a reactance of one of said tuned circuits in circuit with a reactance of the other of said tuned circuits, to thereby simultaneously vary the tuning of and coupling between said circuits.

4. In a tuned coupling device, the combination of an inductive reactance, a capacitive reactance having one connection in common with said in-

ductive reactance, said reactances comprising a tuned circuit, a second inductive reactance, a second capacitive reactance having one connection in common with said second inductive reactance, said last named reactances comprising a second tuned circuit, said first tuned circuit and said second tuned circuit being resonant to substantially the same frequency and being electromagnetically coupled one to another, low impedance means connecting said first tuned circuit and said second tuned circuit, and switching means for effectively including a selected portion of a reactance of one of said tuned circuits in circuit with a reactance of the other of said tuned circuits, to thereby simultaneously vary the tuning of and coupling between said circuits.

5. In a tuned coupling device, the combination of an inductive reactance, a capacitive reactance having one connection in common with said inductive reactance, said reactances comprising a tuned circuit, a second inductive reactance, a second capacitive reactance having one connection in common with said second inductive reactance, said last named reactances comprising a second tuned circuit, said first tuned circuit and said second tuned circuit being coupled one to the other, low impedance means connecting said first tuned circuit and said second tuned circuit, and switching means for connecting a reactance of one of said tuned circuits with one of a plurality of tapped points of a reactance of said other tuned circuit to include the former reactance in circuit with a portion of the latter reactance in at least one switch position and to thereby simultaneously vary the tuning of and coupling between said circuits.

6. In a tuned coupling device, the combination of an inductive reactance, a capacitive reactance having one connection in common with said inductive reactance, said reactances comprising a tuned circuit, a second inductive reactance, a second capacitive reactance having one connection in common with said second inductive reactance, said last named reactances comprising a second tuned circuit, said first tuned circuit being electromagnetically coupled to said second tuned circuit, low impedance means connecting said first tuned circuit and said second tuned circuit, and switching means for connecting a reactance of one of said tuned circuits with one of a plurality of tapped points of a reactance of said other tuned circuit to include the former reactance in circuit with a portion of the latter reactance in at least one switch position and to thereby simultaneously vary the tuning of and coupling between said circuits.

7. In a tuned coupling device; the combination of an inductive winding; a second inductive winding coupled to said first winding; a connection, having a low impedance at the operating frequency, between an end of one of said windings and an end of the other of said windings, whereby a low impedance path at said frequency is provided between said windings; a capacitive element in shunt with said second winding and forming a tuned circuit therewith; a second capacitive element having one side thereof connected to the other end of said first winding and forming therewith a second tuned circuit; and switching means for connecting the other side of said second capacitive element to selectable points associated with said second winding, for including not more than a minor portion of said second winding in circuit with said first winding, to

thereby simultaneously vary the tuning of and coupling between said circuits.

8. In a tuned coupling device; the combination of a tuned transformer including a first inductive winding and a second inductive winding coupled thereto; a connection, having a low impedance at the operating frequency, between an end of one of said windings and an end of the other of said windings, whereby a low impedance path at said frequency is provided between said windings; a capacitive element in shunt with said second winding and forming a tuned circuit therewith; a second capacitive element having one side thereof connected to the other end of 15 said first winding and forming therewith a second tuned circuit; and switching means for connecting the other side of said second capacitive element to selectable tapped points on said second winding, for including not more than a minor portion of said second winding in circuit with said first winding, whereby a selected minor portion 10 of said second winding may be included in circuit with said first winding to thereby simultaneously vary the tuning of and coupling between 20 said circuits.

9. In a tuned coupling device, the combination of a tuned transformer including a first inductive winding and a second inductive winding coupled thereto; a connection, having a low impedance at the operating frequency, between an end of one of said windings and an end of the other of said windings, whereby a low impedance path at said frequency is provided between said windings; a capacitive element in shunt with said second winding and forming a tuned circuit therewith; a second capacitive element having one side thereof connected to the other end of said first

winding and forming therewith a second tuned circuit; said windings and their respective associated capacitive elements comprising tuned circuits which are resonant at substantially the same frequency; and switching means for connecting the other side of said second capacitive element to selectable tapped points on said second winding, for including not more than a minor portion of said second winding in circuit with said first winding, whereby a selected minor portion 10 of said second winding may be included in circuit with said first winding to thereby simultaneously vary the tuning of and coupling between 15 said circuits.

10. In a tuned coupling device; the combination of a tuned transformer including a primary winding and a secondary winding coupled thereto; a connection, having a low impedance at the operating frequency, between an end of one of said windings and an end of the other of said windings, whereby a low impedance path at said frequency is provided between said windings; a capacitive element in shunt with said secondary winding and forming a tuned circuit therewith; a condenser having one side thereof connected to the other end of said primary winding and forming therewith a second tuned circuit; and switching means for connecting the other side of said condenser to selectable tapped points on said secondary winding, for including not more than a minor portion of said secondary winding in circuit with said primary winding, whereby a selected minor portion of said secondary winding may be included in circuit with said primary winding to thereby simultaneously vary the tuning of and coupling between 25 said circuits.

HARRY J. LYMAN.
